UNITED STATES PATENT OFFICE

ARTHUR W. ALTVATER, OF ST. LOUIS COUNTY, MISSOURI

ORNAMENTING DIE

Application filed January 4, 1929. Serial No. 330,191.

This invention relates to ornamenting dies for forming ornamental demarcations in or upon the surfaces of leather and other materials.

5 An object of the invention is to provide a die of the character mentioned including a rigid base having a marking device connected thereto, and a support or platen for the work equipped with gages for locating 10 the work in proper position for operation of a machine to press the work into contact with the marking devices.

Another object of the invention is to provide a die of the character mentioned having 15 means for forming indented outlines and demarcations in or upon the surface of the material and also having means for puncturing the material.

Other objects will appear from the following description, reference being made to the accompanying drawings in which

Fig. 1 is a plan view of one embodiment of my improved die.

Fig. 2 is a front elevation.

25 Fig. 3 is a cross sectional view approximately on the irregular broken line 3—3 of Fig. 1.

Fig. 4 is a plan view of a piece of material showing the outlines and demarcations 30 formed thereon by my improved die.

Fig. 5 is a plan view of another form of die embodying features of the invention.

Fig. 6 is a front elevation of the die shown 35 in Fig. 5.

Fig. 7 is a cross sectional view on the irregular broken line 7—7 of Fig. 5.

40 Fig. 8 is a plan view of a piece of material having ornamental demarcations thereon formed by my improved die.

The base 1 is of rigid material, though not essentially metallic, and has a number of holes 2 in the upper side thereof for receiving the lower ends and heads of guide elements 3, the upper ends of certain of which have rigid engagement with plates 4 constituting work supports or platens for supporting the work; while the upper ends of others of said guide elements 3 have rigid engagement with a gage supporting plate 5.

50 A plate 6 of metal or other appropriate

material is detachably secured upon the base 1 by a number of screws 7. The screws 7 also pass through the base flanges 8 of dies 9 (Fig. 3). Thus the screws 7 attach together the die bodies 8—9, the plates 6 and the base 1. 55

The guide elements 3 project through holes in a plate 10 which is supported by the plate 6. Heads 11 of the guides 3 are received within the holes 2 and serve to limit extent of upward movement of the platens or work 60 supports 4 and the gage support 5. For, while the heads 11 are freely movable within the holes 2, these heads 11 cannot pass through the holes in the plate 10 through which the guides 3 are freely movable. The 65 plate 10 is provided with holes 12 in which the die elements 8—9 are received.

A number of springs 13 extend through holes in the plate 6 and 10 and into spring seats 14 in the base 1. These springs are 70 of adequate number and location to support the platens or work supports 4 and the gage support 5 in the same horizontal plane which is the highest position to which the heads 11 of the guides 3 permit said parts to be 75 moved. The number and tension of these springs is such that about the same pressure is required to depress either one of the platens 4 or the gage support 5. That is to say, the spring resistance to the depression of either 80 platen 4 and the gage support 5 is about the same. The plate 10 is detachably secured upon the plate 6 by screws 15 passing through said plate 10 and through the plate 6 and engaging in threaded holes in the base 1. Access 85 may be had to the screws 15 for purpose of placement and removal thereof through holes 16 in the platens 4 and the gage support 5.

In the embodiment of the invention shown 90 the dies 9 are constructed and designed to form indented outlines in or on the surface of leather and like material and, for this purpose, the upper ends of the die parts 9 have dished or rounded depressions 17 therein, 95 leaving a marginal rib 18 of sufficient sharpness to form a permanent outline in or on the surface of the leather or the like, but not of sufficient sharpness and depth to cut through the leather and the like. 100

This produces ornamental outlines upon or in the surface of the leather or the like such as shown at 22 (Fig. 4) and which I designate inlay ornamentations, because the 5 opposite side of the leather from the side on which the ornamentations are formed is not cut or broken and the appearance on the outside is that of an inlaid ornamentation.

The present invention also 10 comprises means for puncturing the leather or the like to form lines in simulation of stitches or for other purposes. These punctures may be made entirely through the leather or other material or merely through one surface there- 15 of, depending upon the length of the puncturing elements. In order to form these puncture lines I provide a row of sharp pins 19 between each of the platens or work supports 4 and the adjacent edge of the gage 20 support 5. Thus the adjacent edges of said platens and said gage support are spaced apart to provide an intervening space 20 through which the puncturing pins 19 may project when the work supports and the gage 25 supports are depressed by operation of the machine in which the die is mounted. As shown, these puncturing pins form an irregular row or series along the edges of the platens or work supports 4 so that, when the 30 piece of material 21 is placed upon the die and the machine is operated, ornamental indentations 22 will be formed by the die ends 17-18 and a row of indentations or punctures 23 will be formed by the pins 19.

35 Facing each platen or work support 4 a gage 24 is located upon the gage support 5. The edges of the gages 24 conform to the shape of the edge of the piece of material 21 that is to be ornamented. Thus, by engaging 40 the edge of the piece 21 against the edge of the gage 24, it will be known that the work is properly positioned for operation of the machine to produce the ornamentations 22 and 23.

45 In the construction shown in Figs. 5, 6 and 7 the platens or work supports 25 are supported by springs 26 located in spring seats 27 in the rigid base 28. These springs 26 are of adequate number and location to support 50 the platens or work supports 25 and the gage support 29 in the same horizontal plane which is the highest position to which said springs are permitted to move said platens and supports. Guides 30 have their upper ends rigid- 55 ly connected with the platens 25 and with the gage support 29 and project through holes in a plate 31. The heads 32 on the lower ends of the guides 30 operate freely in holes 33 in the base 28 but are too large to pass 60 through the holes in the plate 31 through which the stems of the guides are freely movable. A plate 34 is removably located upon the base 28 and in this form of the invention substitutes for the plate 6 in the embodiment 65 of the invention first described. The

plates 31 and 34 are secured or attached to the base 28 by screws 35 passing through said plates and engaging in threaded holes in the base. These screws are accessible for placement and removal through holes 36 through 70 the platens 25 and the gage support 29.

In this form of the invention the edges of the platens 25 are spaced from the adjacent edges of the work support 29, leaving spaces 37 of sufficient width to accommodate the rows of indenting or cutting or puncturing devices 38. So, also, the platens 25 may be formed with slots 39 to receive row 40 of the ornamenting devices. The upper ends of these ornamenting devices may terminate in the same plane or not, as desired, and may be formed with cutting edges 41 (Fig. 7) which will cut only partially through the work or entirely through the work, as desired. These ornamenting devices are in the form of pins projecting upwardly through the plate 31 and having their lower ends arranged to bear upon the plate 34. The gage plate 29 has gages 42 thereon which may be in the form of lugs or projections, as shown 80 in this embodiment of the invention, or may be of varied forms, as desired. These gages are adapted to serve as abutments for edges of the work pieces 43 so as to position said pieces on the die for subsequent operation 95 of the machine which will repress the gages and the platens and thereby the work uniformly so as to cause the ornamenting devices 38 and 40 to produce the desired ornamentations in, through or upon the work. 100

From the foregoing it will be seen that a single base may be used for different types of ornamenting dies or each ornamenting die may be provided with its own particular base, as desired. Further, while I have shown the gage plates and the platens in separate pieces, it is apparent that they will be operated properly by the machine so as to produce 105 ornamentations of uniform character upon pieces of work passed successively through the machine containing the die. Moreover, the fact that the gage support is separate from the work supports or platens will permit the gage support to be depressed to a greater extent as may be desirable in some 110 instances in order that the gages may pass downwardly to a sufficient extent to permit the plunger of the machine to contact with the work so as to press the work positively against the ornamenting dies. In some or 115 most instances, a strip of paper is interposed between the plunger of the machine and the work, but, since this feature of leather ornamenting machines is well known, I have not illustrated the same in the drawings. 120

As a result of the operation of the machine upon a die such as shown in Fig. 5, the piece of work is formed with two curved rows 44 of ornamentations made by the ornamenting dies 38 and with a row 45 of ornamenta- 125 130

tions produced by the ornamenting dies 40 along one marginal portion of the piece of work, as, for instance, a portion of a shoe upper.

5 This invention may be otherwise varied than as specifically described in order to produce varied forms of ornamentations upon different shapes of material. In describing these two forms specifically, I do not restrict 10 myself thereto, but contemplate the use of such variations as may be found desirable in order to operate upon different shapes of material and to produce different designs of ornamentations thereon, whether such designs include perforations through the material, or surface ornamentations only, or both perforations through the material and surface ornamentations.

I claim:

20 1. A die of the character described comprising a rigid base having holes therein, springs seated on said base, a plate rigid and removably attached to said base and having holes through which said springs extend, guide elements extending through said plate and being movable into said holes in said base, a work supporting platen attached to said guide elements and seated on said springs, means on said guide elements cooperating with said plate to limit extent of movement of said platen by said springs, a die rigid with respect to said plate and said base laterally from the edge of said platen, and a resiliently supported gage for positioning the work upon said platen.

25 2. A die of the character described comprising a rigid base, a work supporting platen, a gage device for supporting and gaging a lateral marginal portion of the work, a die rigid on said base, devices for supporting and guiding said platen and said gage and permitting movement of said platen and said gage as required to press the work thereon against said die, and means for removably securing said devices to said base for operation as aforesaid.

30 3. A die of the character described comprising a base, a plate, dies rigid on said plate, means for releasably securing said plate on said base, platen and gage elements having holes therethrough permitting access to said means for placement and removal thereof, means for supporting said platen and gage elements for movement toward and away from said base, and a die element rigid on said base for operating against the work mounted on said platen and gage elements.

35 4. A die of the character described comprising a rigid base member, separate die and work supporting elements, detachable means for securing to said base different selected die and work supporting elements, and gages for the work mounted on and supported by said work supporting elements.

5. A die of the character described comprising a rigid base member, separate die and work supporting elements, means for securing selected forms of die elements in rigid connection with said base, members 70 for securing to said base selected work supporting elements corresponding to said die elements, and ornamenting devices in rigid connection with said members in predetermined relationship to said die elements. 75

6. A die of the character described comprising a rigid base, means for detachably securing to said base selected forms of ornamenting dies, work supports, members for detachably securing to said base selected 80 forms of work supports for cooperation with the selected dies, and ornamenting elements in rigid connection with said members.

7. A die of the character described comprising a rigid base, means for securing to 85 said base selected forms of ornamenting dies, members for securing to said base selected work supports corresponding to selected dies, springs for supporting the work supports, and gages for the work mounted on and supported by said work supports.

8. A die of the character described comprising a rigid base, means for securing to 90 said base selected forms of ornamenting dies, members for securing to said base selected work supports corresponding to selected dies, 95 springs for supporting the work supports, gages for the work supported by said work supports, and ornamenting elements supported by said members in predetermined relationship to said dies. 100

9. A die of the character described comprising a base having holes therein for the operation of guides, springs supported by 105 said base, a plate, guides mounted for sliding movements through said plate and into said holes in said base, a work supporting platen rigidly attached to the upper ends of said guides and seated upon said springs, an ornamenting die removably attached to said base, and a series of ornamenting elements attached to said plate and spaced from said die. 110

10. A die of the character described comprising a base having holes therein for the 115 operation of guides, springs supported by said base, separate die and work supporting elements, detachable means securing said die in connection with said base, a plate detachably secured to said base, guides connecting said work supporting element and said plate and operating through said plate into said base, and springs supporting said work supporting element in position to support the work above said die. 120

11. A die of the character described comprising a base having holes therein for the operation of guides, springs supported by 130 said base, separate die and work supporting elements, detachable means securing said

- die in connection with said base, a plate detachably secured to said base, guides connecting said work supporting element and said plate and operating through said plate into said base, springs supporting said work 5 supporting element in position to support the work above said die, a gage supported at a distance from said work supporting element, and resilient means supporting said gage.
- 10 12. A die of the character described comprising a gage support, oppositely disposed gages mounted on said support, independently movable work supports spaced from said gage support, a base, ornamenting dies, 15 means for removably securing said ornamenting dies to said base, and detachable means for securing said gage support and said work supports to said base in proper cooperative 20 relationship with each other and with said dies.
13. A die of the character described comprising a rigid supporting base, ornamenting dies removably attached to said base in spaced relationship, a gage support, gaging 25 means supported by said support in position for locating separate pieces of work for simultaneous treatment by said dies, and separate work supports for supporting the work 30 in position for treatment by said dies and against said gages.
14. A die of the character described comprising a rigid supporting base, ornamenting dies removably attached to said base in spaced relationship, a gage support, gaging 35 means supported by said support in position for locating separate pieces of work for simultaneous treatment by said dies, separate work supports for supporting the work 40 in position for treatment by said dies and against said gages, and ornamenting elements extending between said gage support and said work supports.
15. A die of the character described comprising a rigid base, a die, means for detachably securing said die in rigid connection with said base, a plate, means for detachably securing said plate in rigid connection with said base, separate work supporting and gaging means, springs for supporting said work 45 supporting and gaging means for relative movement and for movement toward and away from said plate, and guides operating through said plate and rigidly connected with said work supporting and gaging means.
16. A die of the character described comprising a rigid base, separate work supporting and gaging means, a plate rigidly secured to said base, springs for supporting said work supporting and gaging means above said plate, guides attached to said work supporting and gaging means and operating through said plate, and an ornamenting die 50 detachably secured to said base and extending between said work supporting and gaging means.
17. A die of the character described comprising a rigid base, separate work supporting and gaging means, a plate rigidly secured to said base, springs for supporting said work supporting and gaging means above said plate, guides attached to said work supporting and gaging means and operating through said plate, an ornamenting die 55 detachably secured to said base and extending between said work supporting and gaging means, and a series of ornamenting elements rigid with said plate and projecting between said work supporting and gaging 60 means.
18. A die comprising a rigid base, a plate, means detachably securing said plate in connection with said base, supporting and gaging means for shoe parts, means for forming lines along the shoe parts in simulation of stitches, and means for forming embossed outlines on the surfaces of the shoe parts in definite predetermined relationship to said lines and simultaneously with the formation of said lines.
19. A die for producing ornamental outlines upon the surface of the leather or the like comprising a rigid supporting base, a die rigid on said base for forming embossed outlines on the surface of the leather or the like, means for forming lines in simulation of stitches in a definite predetermined relationship to the embossed outlines, means for supporting the work in position for operation against said line forming and embossing means, and gages for locating the work in proper relationship for operation of said line forming and gaging means.
